Nicholas S. Fedder, of Troy, N. Y.

Assignor to

Cox, Church and Co., of Troy, N. Y.

Letters Patent No. 2157, dated Aug. 1, 1865.

Design for the Top of a Stove.

.....

The schedule referred to in these Letters Patent and making part of the same.

.....

To all whom it may concern:

Be it known that I, Nicholas S. Fedder, of the City of Troy, in the County of Rensselaer and State of New York, have invented and produced a new and original Design for a Top of a Stove, of which the following is a full, clear and exact description, reference being had to the accompanying photograph of a stove-top embodying my said design.

This design for a stove-top consists of a raised, open-work, oval plate U, made with the annular series of ornamental rises, or between, or alternating with the series of openings W; and mounted on an oval ornamental plate X, and surmounted by an ornamental vase or urn Y; so as to present the appearance represented by the aforesaid photograph.

What I claim as my invention or production and desire to secure by Letters Patent is the design for a top of a stove, as herein set forth.

Eliakim Morse, } Witnesses.
